D7-581

EX

D9532

OR

D 27,562

DESIGN.

—
L. S. IPSEN.

PLATE OR ANALOGOUS ARTICLE.

No. 27,562.

Patented Aug. 24, 1897.

WITNESSES:

William S. Brigg.
Ruben L. Roberts.

INVENTOR:

Ludwig S. Ipse

UNITED STATES PATENT OFFICE.

LUDVIG S. IPSEN, OF MALDEN, MASSACHUSETTS, ASSIGNOR TO THE RICHARD BRIGGS COMPANY, OF MASSACHUSETTS.

DESIGN FOR A PLATE OR ANALOGOUS ARTICLE.

SPECIFICATION forming part of Design No. 27,562, dated August 24, 1897.

Application filed January 14, 1897. Serial No. 619,255. Term of patent 7 years.

To all whom it may concern:

Be it known that I, LUDVIG S. IPSEN, a subject of the King of Denmark, residing at Malden, in the county of Middlesex and State of Massachusetts, have invented and produced a new and original Design to be Used as a Decoration for Plates, Cups, and Analogous Articles of Crockery and Porcelain Ware, of which the following is a specification, reference being had to the accompanying drawing, which shows the same as applied to a plate.

The leading features of this design consist of a border for plates and other articles of crockery and porcelain, defined by two parallel border-lines broken at intervals and the broken ends curved inward, festoons of flowers and leaves attached to these curved ends of the outer border-line by bows of ribbon, and by the same bows wreaths of leaves fastened over the festoons. Within the circle of each wreath is a conventional "fleur-de-lis."

A further ornament, which may be termed a "coat of arms," to be used in connection with the above-described border, consists of a shield ornamented with the fleur-de-lis, a crown over the top of the shield, and a wreath of leaves tied with a ribbon entirely encircling the whole. This ornament is to be used in the center of plates and dishes of a similar character, as illustrated in the drawing, and upon the sides of deep dishes, such as cups, tureens, &c.

What I claim is—

1. A decorative design for plates and analogous articles of crockery and porcelain ware, comprising two border-lines broken at regular intervals and having between them festoons of flowers and leaves, tied with ribbons at the several breaks in the lines; wreaths of leaves held by the ribbons at the same points and a fleur-de-lis within the said wreaths, substantially as set forth.

2. The decorative design for plates and analogous articles of crockery and porcelain ware, comprising the ornamental border and coat of arms herein described and shown.

LUDVIG S. IPSEN.

Witnesses:

WILLIAM S. BRIGGS,
REUBEN L. ROBERTS.